UNITED STATES PATENT OFFICE

MILTON HINKLEY, OF BENTON HARBOR, MICHIGAN

CARTON

Application filed September 25, 1926. Serial No. 137,639.

This invention relates to cartons in general, but more particularly to egg cartons and fillers therefor, of the kind in which a dozen eggs are sold at the stores. Ordinarily, these cartons are made to collapse or fold flat, so that they may be conveniently stored or shipped.

Generally stated, the object of the invention is to provide a form of carton which will 10 nest one within another, to form a compact stack of cartons for storage or shipment, with a flexible cover integral with the rear side wall of each carton, the covers being also 15 preferably adapted to nest together at one side of the stack, thus obviating the necessity of using a foldable or collapsible construction for an egg carton of this character, the invention in this case being in the nature 20 of an improvement on the construction shown and described and claimed broadly in prior application Serial No. 127,267, filed August 5, 1926.

To the foregoing and other useful ends, the invention consists in matters hereinafter set 25 forth and claimed and shown in the accompanying drawings in which—

Fig. 1 is a perspective of an egg carton and 30 filler involving the principles of the invention, showing the cover open.

Fig. 2 is a transverse section of said carton and filler, showing the cover closed.

Fig. 3 is a longitudinal vertical section on line 3—3 in Fig. 2.

Fig. 4 is a plan view of the blank from 35 which the carton is made.

Fig. 5 is a transverse section of a stack of nested cartons.

Fig. 6 is a perspective of one end portion 40 of the carton, in partially folded condition.

As thus illustrated, the blank comprises the bottom section 1, rear side section 2, front side section 3, the cover section 4, and the cover flap section 5, as shown in Fig. 4 of the drawings. For the formation of the end walls 45 of the carton, the blank also has the sections 6, 7, 8, 9 and 10 at each end thereof. It will be seen that the score lines or crease lines 12, 13, 14, 15, 16, 17, 18, 19, 20, 21 and 22 are so located as to form the different 50 sections of the blank as shown and described,

to obviate the cutting through of the material, and to form stronger end walls for the carton, as will more fully appear.

When the blank is folded, the different sections thereof assume the positions shown 55 in Fig. 1 of the drawings, and a single staple 23 is inserted through the folded end wall portions, at each end of the carton, thereby to hold the blank in its folded condition.

When the carton is thus completed, the 60 front and rear sides 3 and 2 are inclined outwardly, as shown in Fig. 2 of the drawings, and the end walls of the carton are also inclined outwardly, as shown in Fig. 3 of the drawings. But because there are no cuts in 65 the blank, and only score lines or crease lines, there are no cracks or crevices anywhere, and the carton is practically leak-proof, as any liquid if placed in the carton could not leak out. And, in addition, the scoring or creasing of the blank is comparatively simple and 70 inexpensive, and the blank thus formed folds readily and easily, and the end walls are strong and stiff and the box or carton is serviceable.

The cartons when thus made can be nested 75 as shown in Fig. 5 of the drawings, for shipment or storage, in an indvantageous manner. This is because, as illustrated in Fig. 80 6, which shows one end of the carton partially folded, the form of the blank and the folding thereof serve to produce a downwardly tapered carton or box, the sides and ends being inclined outwardly, and hence the cartons or boxes of this kind are advantageously 85 nested and stacked as shown.

The filler 24, shown in Figs. 1, 2 and 3, can 90 be of any suitable known or approved form, being of a size to accurately fit the bottom of the box or carton, so that the filler cannot shift sidewise or endwise. But because the walls of the carton or box are inclined outwardly, there will be some space between the upper edges of the front and rear sides of the box and the adjacent sides of the filler, and some space between the ends of the filler 95 and the upper edges of the end walls, as shown in the drawings.

Thus the end walls of the carton are 100 formed from sheet material which is not cut

or severed at any point, the material being merely folded and doubled back upon itself, and the end walls being thus formed of sections of sheet material having only fold lines between them. The sections 7, 8 and 9, at 5 each end of the carton, thus form upwardly tapered outside end portions of double thickness, as the sections 7 and 9 are folded against the inner surface of the section 8 at each end of the carton.

10 Without disclaiming anything, and without prejudice to any novelty disclosed, what I claim as my invention is:

1. In a carton formed from a single blank, 15 the combination of flat end walls inclined outwardly, flat front and rear side walls inclined outwardly at an angle, a flat bottom wall, and a flexible rectangular cover integral with the rear side wall, whereby each 20 carton body is rectangular at top and bottom and shaped to nest one carton within another, to form a stack of cartons for shipment or storage, with the cover of each carton protruding from the side of the stack, said 25 end walls being formed of sheet material folded and doubled back upon itself and creased to obviate cutting through the material and to form stronger end walls to protect the contents of the carton, providing inside 30 overlapping flaps having straight end edges, and an outside upwardly tapered flap of more than one thickness for each end of the carton, forming an overlap inside each end wall, with the straight upper edge of each outside flap 35 necessarily positioned flush with the straight upper edges of the inside flaps in the folding of the blank to obtain said inclined angle of the front and rear walls, said inside end edges extending downward from the top edge 40 of each flap to points below, with the overlap between these two edges at each end of the box, and with each outer flap wide enough to cover the entire overlap, each inside flap comprising only a single thickness of the blank, 45 whereby said overlap is of double thickness only.

2. A structure as specified in claim 1, and 50 a filler for each carton, when the carton is released from the stack for use, adapted to rest on said bottom between said outwardly inclined side and end walls.

3. A structure as specified in claim 1, said 55 cover adapted to nest with the cover of another carton, so that the covers are all at the same side of the stack.

4. A structure as specified in claim 1, and 60 a filler for each carton, when the carton is released from the stack for use, adapted to rest on said bottom between said outwardly 65 inclined side and end walls, said filler having vertical sides and ends, but the length and width of the filler being substantially the same as said bottom, whereby the lower portions of the side and end walls hold the filler 75 against displacement.

5. A structure as specified in claim 1, having means forming the contents thereof, said cover having a flap for insertion inside the outwardly inclined front side wall, this front side wall and the adjacent side of the 70 contents forming in cross section a downwardly tapered air space for said flap.

6. A structure as specified in claim 1, the 75 upper end of each outside end flap being substantially the same in width as said overlap.

Specification signed this 16th day of September, 1926.

MILTON HINKLEY.
